UNITED STATES PATENT OFFICE.

TRULS LOKEN, OF KENOSHA, WISCONSIN, ASSIGNOR, BY MESNE ASSIGNMENTS, TO
F. C. AUSTIN MACHINERY COMPANY, A CORPORATION OF ILLINOIS.

TRENCHING MACHINE.

Application filed January 2, 1918. Serial No. 209,860.

To all whom it may concern:

Be it known that I, TRULS LOKEN, a citizen of the United States of America, and resident of Kenosha, county of Kenosha, and State of Wisconsin, have invented a certain new and useful Improvement in Trenching Machines, of which the following is a specification.

This invention relates to excavating machines of that kind in which a ring or spokeless wheel is mounted in rear of the excavator body, and provided with a series of scoops or buckets extending around the periphery thereof, so that by rotating the ring or spokeless wheel in the ground, while the excavator is slowly moving forward, a trench will be cut in rear of the excavator body.

Generally stated, the object of the invention is to provide a novel and improved trench-cutting-machine of the foregoing general character.

Another object is to provide an improved construction and arrangement whereby the buckets or scoops are operative to cut into the ground and carry the excavated dirt upward, and to automatically dump their loads when they reach the point of discharge at the top of the ring or spokeless wheel, without the necessity of using gates or doors for the rear ends of said buckets, thereby to simplify the construction and render the machine more certain and reliable in operation, and less liable to break or get out of order.

It is also an object to provide certain details and features of construction and combinations tending to increase the general efficiency and desirability of a rotary trenching-machine of this particular construction.

To these and other useful ends, the invention consists in matters hereinafter set forth and claimed.

In the accompanying drawings:

Figure 1 is a side elevation of a trenching machine embodying the principles of the invention, with the forward end thereof broken away for convenience of illustration.

Figure 2 is a plan of the excavating apparatus of said machine.

Figure 3 is a longitudinal section on line 3—3 in Figure 2.

Figure 4 is an enlarged vertical transverse section on line 4—4 in Figure 3.

Figure 5 is a detail section on line 5—5 in

Figure 6, showing one of the scoops or buckets in front elevation.

Figure 6 is a section on line 6—6 in Figure 5.

Figure 7 is a perspective of one of the scoops or buckets.

As thus illustrated, the invention comprises a body frame or chassis A provided at its rear end with suitable traction means B, and having its forward end provided with steering wheels (not shown) and with an engine C or other suitable motive power for not only driving the machine forward, through the medium of said traction means, but also for operating the rotary ring or spokeless wheel D in rear of said body or chassis. This spokeless wheel is in the form of a ring composed of two flat rings 1 and 1 spaced apart to receive the webs of angle iron rings 2, which latter are secured to the rings 1 by bolts 3, or by any suitable means, and the construction is such that the periphery of the wheel is flat in cross-section, but provided with a central slot 4 extending throughout the circumference thereof. A swinging frame E is pivoted on the rear end of the body frame A, by means of a transverse shaft e, so that this frame is adapted to swing up and down behind the excavator body. Said frame E is provided with a depending framework F upon which are mounted the wheels f that are formed to engage the inner edges of the rings 1 of the spokeless wheel, whereby the latter is held in position to rotate about a transverse axis. The frame E is provided with a transverse shaft 5 having pinions 6 which engage the cogs 7 on the sides of the rings 1, and which thereby not only support the wheel but serve also to rotate the latter about its transverse axis. Sprocket chains 8 connect the shaft e with the shaft 5, whereby rotation of the shaft e will rotate the shaft 5 and thereby rotate the spokeless wheel. In the slot 4 are pivoted the shanks 9 of the buckets or scoops 10, which latter are in the form of trough-shaped plates having said shanks applied to the centers thereof, so that each bucket is practically divided by its shank into two compartments. The holes 11 in the shanks of the buckets may receive the bolts 3, so that these bolts not only hold the parts of the wheel together but serve also as the pivots for the buckets. A cam 12 is

90

100

105

mounted on the frame E, in position to engage the curved tail portions 13 of the shanks 9, so that the fixed scrapers 14, which are suitably mounted on the upper frame 15, 5 may pass through the buckets, thereby to scrape out the dirt and cause the same to fall into the laterally extending chutes or spouts 16, which latter are of sheet metal and may be formed integral with said 10 scrapers or cleaners 14, and which may be removably held in place by screws 17 or other suitable means.

The shaft e can be rotated in any suitable or desirable manner; for example, it may be 15 connected by a sprocket chain 18 with the rotary shaft 19 on the chassis or motor truck body, and this shaft 19 can be connected with the motor or engine in any suitable or desired manner. The shaft 19 is rotated in 20 a direction to rotate the shaft 5 in such a direction that the buckets 10 move upward in front of the spokeless wheel and downward in rear thereof, thus cutting the trench as the machine slowly moves forward.

25 The frame E is preferably provided with some means for lifting it upward, so that the spokeless wheel may be lifted out of the trench. For this purpose, the frame 15 may be provided with a bail 20 connected with 30 a boom or brace 21 pivoted at 22 on the body frame, and the upper end of this brace or boom may be provided with a sheave 23 for the hoisting or lifting cable 24, which latter is connected to the auxiliary body 35 frame 25 at 26, and supported by the sheave 27 on said auxiliary frame. The other end portion of said hoisting cable is wound on the drum 28 on the body of the machine, and this drum 28 can be operated through 40 the medium of any suitable power-transmitting-connection, so that when the cable is wound thereon the brace or boom 21 will be pulled forward, and the frame E will thereby be lifted upward, (see dotted lines 45 in Figure 1) so that the rotary spokeless trench-cutting wheel will be lifted out of the ground.

50 The operation is as follows:—The spokeless wheel is lowered into the ground, while it is rotating, and when it reaches the required depth the traction means are then started to propel the machine slowly forward. Each bucket while passing below the wheel assumes a digging position, as the 55 pressure of the soil against the cutting edge G of the bucket will keep its rear edge 9 pressed tightly against the flat periphery of the spokeless wheel, so that in this position the bucket is practically closed at its rear 60 end, thus holding the dirt as the bucket moves upward toward the dumping position. As the bucket reaches the dumping position, its tail portion 13 will ride upward upon the stationary cam 12, and this will tilt the 65 bucket slightly forward on the wheel, thus

opening its rear end, and thereby permitting the two stationary and oppositely disposed scrapers or cleaners 14 to pass through the bucket and thereby dislodge the load therefrom. As the buckets move downward, and 70 strike the ground, they are tilted backward to digging position so that their forward cutting edges scrape up another load of dirt. As the buckets rise, they preferably 75 pass through a sheet metal tunnel or shield H suitably mounted on the frames E and 15, but in the balance of their travel they are exposed and not enclosed. In this way, the buckets are practically closed at their rear ends, but not by gates or doors, and 80 in this way the construction obviates the necessity of using certain devices which have heretofore been considered necessary or desirable, but which have not been entirely satisfactory. The simplified construction 85 thus brought about by the invention is strong and serviceable, is capable of efficient work in heavy soil, such as hard clay, without danger of breakage, and at the same 90 time the mud carried in the buckets will be positively ejected or removed therefrom by the stationary scrapers or cleaners 14, in the manner previously described. Also, the buckets are positively moved into position to allow the cleaners to pass successively 95 through the buckets, so that the cleaners or scrapers will not retard or interfere with the rotation of the spokeless wheel.

When the buckets G are in tilted position, 100 after passing the cam 12, their curved outer surfaces or peripheries are then on a circle which is concentric to the periphery of the ring or rotary member D, and it follows, 105 therefore, that the buckets when in operative position extend farther away from the axis of said member than when in any tilted position. As shown, the pivots of the buckets are so located that the cutting edges of the buckets are a little ahead of the pivots, 110 when the buckets are in operative position, and hence the buckets extend farther away from the periphery of the ring or the rotary member D when they are in operative position than when in any tilted position. In 115 this way, the buckets will descend into the trench in tilted position, and will then begin to tilt backward about their pivots as soon as they begin to exert pressure against the breast or front end of the trench, and by 120 tilting backward the buckets are caused to extend farther outward from the periphery of the ring or rotary member and into the dirt to be cut away. Also, it will be seen that the pivot of each bucket is substantially 125 midway between the front and rear edges of the bucket, when the bucket is in tilted position, so that the front edge of the bucket is some distance ahead of said pivot when the bucket is in operative position. In this 130 way, the buckets are adapted to effectively

discharge their loads as they pass over the cleaner, and operate in the desired manner in the trench.

With the combination and arrangement 5 shown and described, the buckets are held in cleaning position while passing the cleaners 14, and while revolving rearward at the top of the rotary ring or spokeless wheel. The buckets after discharging their loads, 10 enter the ground and are filled while they are revolving forward at the bottom of said rotary ring or spokeless wheel.

The angle rings 2 and the cog rings or 15 internal gears 1 constitute a spokeless wheel, so to speak, which is rotated as explained, in a direction to cause each bucket to cut forward at the bottom of the trench and then upward against the breast of the trench, while the trenching machine or excavator is 20 moving slowly forward in the desired direction of travel thereof. In this way, moreover, each bucket is tilted by engagement of its cam 13 with the cam-engaging means 12 while the bucket or scoop is traveling in a 25 direction opposite to that of the desired direction of travel of the excavator or trenching machine, at the top of the wheel, so that each bucket carries a load forward and then upward at the front side of the wheel, and 30 then rearward at the top of the wheel, each load being thus automatically dumped or discharged while a bucket directly below is moving forward to take up a load as it approaches the breast or curved end of the 35 trench.

What I claim as my invention is:—

1. In a traveling excavator, a pivoted bucket, means for moving said bucket forward in the direction of travel of the excavator and then upward to cut the ground and take up a load of dirt, a cam connected with said bucket, stationary controlling means for engaging said cam to tilt said bucket into cleaning position, and a cleaner disposed in position to pass through the moving bucket when the latter is thus tilted and held in cleaning position.

2. In a traveling excavator, a pivoted bucket, means for forcing said bucket into the breast of a trench to cut the ground then elevating it to carry a load of dirt to a discharge point, a cam connected with said bucket, stationary controlling means for engaging said cam to tilt the bucket into a cleaning position, and a cleaner disposed in position to pass through the moving bucket when the latter is thus tilted.

3. In a traveling excavator, a pivoted bucket, means for moving said bucket into the breast of a trench to cut the ground and to elevate it to take a load of dirt to a discharge point, a cam rigid with the bucket, a stationary controlling means at the discharge point for engaging the cam to tilt the bucket into a cleaning position, and a cleaner

disposed in position to pass through the moving bucket when the latter is thus tilted and held in cleaning position.

4. In a traveling excavator, a pivoted bucket, means for moving said bucket into 70 the breast of a trench to cut the ground and to elevate it to take a load of dirt to a discharging point, an arm on said bucket, a stationary device for engaging the arm to tilt the bucket into cleaning position, and 75 a cleaner disposed in position to pass through the moving bucket when the latter is thus tilted and held in cleaning position.

5. In an excavating apparatus, the combination of a movable support, a digging 80 and conveying bucket provided with a shank pivoted on said support, means for positively operating said support thereby causing a bucket to have the desired cutting action in the ground, a stationary cam, 85 means rigid with the shank adapted for engagement with the cam to tilt a bucket into a cleaning position, and a cleaner arranged to pass through the bucket at the desired point to discharge therefrom. 90

6. In an excavating machine, the combination of a movable support, a digging and conveying bucket provided with a shank which is pivoted on said support, 95 means for positively operating said support and thereby causing said bucket to have the desired cutting action in the ground, means for raising and lowering said support, so that said bucket may operate at the desired depth in the ground, a 100 cleaner arranged to pass through said bucket at the desired point of discharge thereof, a stationary cam and means rigid with said shank to engage said cam thereby to tilt said bucket into cleaning position, and for holding the bucket in this position while passing said cleaner.

7. In a trenching machine, the combination of a pair of flat-sided rings spaced apart and provided on their outer sides 110 with cog teeth, a pair of rings of angle iron formation disposed between said flat-sided rings, buckets provided with centrally disposed shanks inserted between the two angle iron rings, a cam on the shank 115 of each bucket, bolts inserted through said rings and shanks to form pivots for the buckets, pinions to engage said cog teeth, means to support said rings for rotation about a horizontal and transversely disposed axis, a pair of cleaners disposed in position to pass through said buckets, 120 and means to engage said cams to tilt the buckets into cleaning position and to hold said buckets in such position while passing 125 said cleaners.

8. A structure as specified in claim 7, in combination with means for rotating said rings in a direction to cause each bucket to cut forward at the bottom of the trench, and 130

then upward against the breast of the trench, said cam-engaging means being disposed in position to tilt the buckets while the latter are at the top of said rings, so that each bucket is tilted by engagement of its cam with said means while traveling in a direction opposite to the direction of travel of the trenching machine.

9. In a traveling excavator, the combination of an annular member arranged to rotate about an axis extending transversely of the direction of travel of said excavator, excavating buckets pivoted on said member, means for positively rotating said member to cause said buckets to cut for-

ward at the bottom of the excavation, and then upward against the breast thereof, while the excavator is moving forward in the desired direction of travel thereof, stationary cleaning means arranged to pass through the buckets while the latter are upside down and traveling rearward of the excavator at the top of said rotary member, and instrumentalities for causing said buckets to automatically tilt into cleaning position before passing said cleaning means.

Signed by me at Chicago, Cook County, Illinois, this 14th day of December, 1917.

TRULS LOKEN.
